UNITED STATES PATENT OFFICE.

ELMER H. RECORDS, OF SPOKANE, WASHINGTON.

STILL.

Application filed February 24, 1925. Serial No. 11,132.

My present invention relates to improvements in stills for the distillation of highly volatile gases as carbonic oxide gas, and setting free hydrogen gas from coal by the chemical action of superheated steam for the production of heating gases to be used in stoves or furnaces and for the production of coke in the form of the solid carbon as a residue after distillation. Both the gaseous and solid products of the distillation provide heating fuels especially adapted for and efficient in use in various ways.

While the apparatus of my invention is capable of uses other than as above set forth, for convenience of description and illustration, I shall hereinafter refer to the appliance as a coal still.

By the utilization of the apparatus of my invention I secure a close, intimate and maximum contact of steam with the entire area of the coal bed which is thoroughly penetrated by the steam to insure a rapid and complete destructive distillation by the heat from the superheated steam for the purpose of carrying off the volatile constituents.

Means are provided for rapidly and with facility charging the still with coal, closing the still, and for discharging the coke residue from the still, while at the same time maintaining in a substantial manner the temperature of the interior of the still.

The invention consists in certain novel combinations and arrangements of parts as will hereinafter be more fully set forth and claimed.

In the accompanying drawings I have illustrated one complete example of the physical embodiment of my invention wherein the parts are combined and arranged in accordance with the best mode I have thus far devised for the practical application of the principles of my invention.

Figure 1 is a vertical central sectional view of a still embodying my invention with a charging bucket therein.

Figure 2 is a transverse sectional view at line 2—2 of Figure 1.

Figure 3 is a top plan view of the still.

Figure 4 is a plan view at the underside of the charging bucket illustrating its drop bottom.

Figure 5 is a detail view of one of the bottom sections with its locking device.

Figure 6 is a view in side elevation showing a tar still which may be used in conjunction with the coal still.

In carrying out my invention I utilize an upright cylinder 1 having a closed bottom 2 and removable lid or cover 3, the latter being hinged at 4 to swing in a horizontal plane 60 on the pivot bolt 4. An eye bolt 5 is provided in the cover for use with a suitable tool or appliance for swinging the cover when required. The hinge bolt 4 is disposed in a horizontal bracket plate 6 which extends laterally a sufficient distance to afford a support for the cover when it is swung open at either side of the pivot bolt, and an upper hinge strap 7 is riveted or bolted to the cover to complete the hinge joint. 70

At the upper end or edge of the cylinder 1 a clamp ring 8 is attached on its exterior, and said ring is provided with an annular horizontal flange 9 having a series of radial notches 10 spaced at regular intervals around 75 its periphery. Between the flange and the cover a gasket 11 is interposed to insure an air and steam tight joint.

The periphery of the cover is fashioned with a series of radial notches 12 complementary to the notches 10 of the flanged ring, and a series of clamp bolts 13 are swiveled or hinged on the flanged ring to swing up into complementary pairs of these notches. Lock nuts 14 on the bolts are employed to clamp 85 the cover over the upper end of the cylinder to insure a steam tight joint while the still is operating.

At the lower end of the cylinder a steam inlet pipe 15 is provided and near the upper end of the cylinder a steam outlet pipe 16 is connected for carrying off the fumes and gases of distillation. The superheated steam is supplied to the cylinder under suitable pressure and passes through the bed of coal and 95 through the still as indicated by the arrows in Figure 1.

The nipple 17 is provided on the outlet pipe for connection with a tar still if desired, and for this purpose interior threads 18 100 are used in the nipple, as seen in Figure 1.

The tar still referred to may be located at a convenient place adjacent to the present still and it may be heated by suitable means for further treatment of the product of this 105 still.

At a suitable place in the cylinder, say approximately one-third the distance from the top of the still, a flanged suspending ring 19 is attached by rivets or bolts, and near the 110 bottom of the cylinder is arranged a series of spaced guide bars 20 attached to the cylinder

wall. The suspending ring and guide bars are for the purpose of supporting and guiding the charging bucket 21 in which the bed of coal is contained, and which as seen in Figure 5 is suspended in the ring within the cylinder with its bottom elevated above the bottom of the cylinder and above the inlet for steam, and its top below the outlet opening for gases. The guides or guide bars center the charging bucket when it is being lowered into the still or cylinder and hold it stationary in the cylinder.

Preferably the charging bucket is cylindrical in cross section and it is of smaller diameter than the cylinder to provide an annular space or chamber 22 between the exterior of the bucket and the inner faces of the wall of the cylinder. A portion of this chamber is also provided beneath the bucket, 20 and as seen in Figure 1 the suspending ring 19 closes the upper end of the annular chamber.

The charge bucket in which the bed of coal is contained is fashioned with an upper open end and is provided with a bail 23 for use in connection with a crane or other bucket-handling device. The walls of the bucket are perforated as at 24 for the admission of steam from the annular chamber or space 22.

On the exterior of the bucket near its upper edge is attached a flanged ring 25 adapted to rest upon the supporting ring 19 in the interior of the cylinder.

At the center of the charging bucket is arranged a tube or standpipe 26, open at its lower end, and with its upper end terminating below the upper edge of the bucket. The upper end of the stand pipe is provided with a foraminous closure or screen 27 which permits passage therethrough of steam from the stand pipe, but prevents coal from the bed falling into or through the pipe.

Lateral braces 28 and 29 form spider frames attached at their outer ends to the bucket for maintaining the stand pipe in upright position at the center of the bucket, and it will be understood that the charge or bed of coal in the bucket may extend above the top spider frame.

The charging bucket is provided with a drop bottom which when opened permits ready discharge therethrough of the coke or residue after distillation. The drop bottom is fashioned in two semi-circular sections 30 and 31 which when closed form a circular disk or closure with a central circular opening 32 for accommodation of the lower end of the stand pipe 26.

These bottom sections are hinged to the bucket at 33 to swing downwardly and inwardly and the sections when closed, are latched or locked in this position by means of spring pressed slide bolts 34 located at the opposite free ends of the swinging sections.

The slide bolts are adapted to engage perforated keepers 35 attached within the bucket and projecting below its lower edge as seen in Figure 5. Guide plates 36 are carried by the bottom sections to guide and retain the bolts, and each bolt has a spring 37 normally holding the bolt in projected position.

The bottom sections are also perforated as indicated at 38 for the passage therethrough of steam to the interior of the bucket and to pass through the bed of coals. The superheated steam under pressure is thus passed upwardly through the perforated bottom of the bucket, through the stand pipe, and also through the perforated walls of the bucket in, order that the entire mass or coal bed may be subjected to the chemical action of the steam for carrying off the gases through the outlet pipe. The gases thus driven off may be gathered and condensed by means of suitable condensers, and separated for various uses as desired.

After one charge of coal in a bucket has been subjected to the action of the superheated steam, for say thirty to forty minutes, the cover is released and swung out of the way for withdrawal of the bucket, and immediately a succeeding bucket with an additional charge therein is lowered into the cylinder, the cover returned to position and locked in place, the steam which during the change has been turned off, is again supplied to the cylinder and the procedure is repeated, without undue waste of steam or material reduction in the temperature of the interior of the still.

The residue or coke remaining in the bucket after the volatile gases have been carried off provides a desirable and smokeless fuel for use in cooking stoves, heating stoves, furnaces and the like, which fuel having had the moisture removed therefrom affords a more inflammable material and furnishes more heat units per pound than is contained in the untreated coal.

When treating extremely fine coal for the extraction of volatile gases a screen of fine mesh may be fixed in the bottom of the bucket to prevent the fine coal from clogging up the openings in the bottom sections.

In Figure 6 a tar still 39 is shown which may be used in conjunction with the coal still to release the volatile gases from the by-product, or for other similar purposes. This still is illustrated merely to indicate one means of disposing of the by-product from the still of my invention.

Having thus fully described my invention, what I claim as new and desire to secure by Letters Patent is—

1. The combination with a still-cylinder having an inlet for steam, an outlet for volatile gases, and supporting means within the cylinder, of a removable charging bucket having a perforated bottom and perforated side walls, and forming an annular steam pas-

sage within the cylinder, and said bucket having a central pipe supported therein, open at both ends and leading to the outside of the bucket.

5 2. A charging-bucket for use with a still comprising a perforated wall-structure, a central pipe within the bucket and supported from its walls, said pipe being open at both ends and leading to the outside of the bucket,

a drop bottom for the bucket comprising 10 hinged, perforated plates adapted to swing outwardly from the center of the bucket, and means for securing said plates in closed position.

In testimony whereof I affix my signa- 15 ture.
